ATTORNEY

UNITED STATES PATENT OFFICE

138,506

DESIGN FOR A COMBINED MIRROR AND PICTURE FRAME

Sarkis Cirkinian, New York, N. Y.

Application June 26, 1944, Serial No. 114,191

Term of patent 3½ years

(Cl. D29—20)

To all whom it may concern:

Be it known that I, Sarkis Cirkinian, a citizen of the United States of America, residing in New York city, county of New York, and State of New York, have invented a new, original, and ornamental Design for a Combined Mirror and Picture Frame, of which the following is a specification, reference being had to the accompanying drawing, forming part thereof, wherein,

Figure 1 is a front elevational view of a combined mirror and picture frame showing by new design.

Figure 2 is a side elevational view thereof, and

Figure 3 is a top plan view, taken in perspective.

The front and rear of the combined mirror and picture frame are identical in appearance, excepting that the front circular member consists of plain glass, whereas the corresponding rear section is mirrored.

I claim:

The ornamental design for a combined mirror and picture frame, substantially as shown and described.

SARKIS CIRKINIAN.
